CLAIM

The ornamental design for a casing for a solar mobile charger, as shown and described.

DESCRIPTION

FIG. 1 is a front-bottom perspective view of an ornamental design for a casing for a solar mobile charger according to a first embodiment of the present invention;

FIG. 2 is a front-side perspective view thereof;

FIG. 3 is a back perspective view thereof;

FIG. 4 is a front view thereof;

FIG. 5 is a back view thereof;

FIG. 6 is a first side view thereof;

FIG. 7 is a second side view thereof;

FIG. 8 is a bottom view thereof;

FIG. 9 is a top view thereof;

FIG. 10 is a front-side exploded perspective view of the ornamental design for a casing for a solar mobile charger; and,

FIG. 11 is a side view thereof, with the exploded panel removed for ease of illustration.

The broken lines shown in FIGS. 1–11 are for illustrative purposes only and form no part of the claimed design.
